UNITED STATES PATENT OFFICE.

WILLIAM S. WESTON, OF DALLAS, TEXAS.

ANTICREEPER FOR RAILWAY RAILS.

Application filed January 31, 1924. Serial No. 608,696.

To all whom it may concern:

Be it known that I, WILLIAM S. WESTON, a citizen of the United States, residing in the city of Dallas, county of Dallas, and State of Texas, have invented certain new and useful Improvements in Anticreepers for Railway Rails, of which the following is a full, clear, and exact description.

My invention relates to improvements on the spring clamp anticreepers set forth in U. S. Letters Patent No. 1,120,258 granted to me December 8, 1914, and No. 1,257,566 granted to me February 26, 1918, whereby three seats for effective bearing on the rail base flanges, actuated by the spring quality of the device, establish and maintain thereon a grip, which in functional operation becomes a double lever grip. My present invention relates more particularly to improvements in the form of the device made from a material of uniform resilient quality; and its primary object is to secure, by the spring clamp action of the form itself, a greater and more positive initial grip at the seats of bearing. The full construction of an anticreeper embodying these improvements together with other novel details of construction utilized to facilitate the installation of the improved device, are herein-after described, and clearly illustrated in the accompanying drawings which form a part of the specification. The novel features are particularly pointed out in the claims.

25 In the drawings:

Fig. 1 is a side elevation of a rail R showing the anticreeper in position against the tie T.

Fig. 2 is an elevation transverse to the rail as seen from the left of Fig. 1 with the tie omitted.

40 Fig. 3 is a plan view of Fig. 1.

Fig. 4 is an elevation transverse to the rail, similar to Fig. 2, with the rail indicated by dotted outline, drawn to illustrate the manufactured shape and relation of the parts.

45 Figs. 5 and 6 illustrate the position of the device at different stages in the process of its installation.

Fig. 7 is a larger scale plan view, similar to Fig. 3, with the rail base shown in dotted outline.

50 Figs. 8 and 9 are vertical sections on the lines 8--8 and 9--9 respectively of Fig. 7,

all drawn for the purpose of illustrating in detail the construction of the three seats of bearing on the rail flanges, the edge of the flange being indicated by dotted lines.

Fig. 10 is an elevation similar to Fig. 1 showing, against a rail base edge indicated by dotted cutline, a preliminary shape of the stock from which the device is formed finally.

The same letters and numerals of reference indicate the same parts in the several views.

Described in general terms, and as seen in the plan view, my anticreeper is a V-form spring clamp device, made of resilient material, provided with three seats for bearing against the rail base edges, one seat at or adjacent the root of the V and one at or adjacent the end of each arm or member. One member of the V passed diagonally beneath the rail is hereinafter called the transverse member while the other member, inclusive of all its parts as seen in the other views, lying along one rail base flange is called the longitudinal member. In the manufactured shape with the transverse member correctly positioned on the rail, with the seat at its end and at the root of the V bearing against opposite flange edges, the third seat at the end of the longitudinal member is made to encroach on the rail seating space by making the angle of the V-form less than required by the rail on which it is to be used. The spring clamping action is obtained by the opening of the angle of the V in the process of installation.

Referring to Figs. 1, 2 and 3 of the drawings, the part indicated by the numeral 1 is the transverse member, 2 is the longitudinal member bent inwardly over the base of the rail at 3 and thence outwardly and downwardly past the edge of the rail base at 4. The downwardly bent part 4 constitutes the tie-abutting member which is braced by having its free end bent back and upwardly at 4^a so as to take a bearing against the underside of member 2 adjacent the root of the V-form. The part marked 5 is the offsetting connection between members 1 and 2 at the root of the V, and 6 is the upturned hook at the free end of member 1. The part 5 and the downwardly bent part 4 furnish two seats, 7 and 8 respectively, for bearing on the edge of one base flange, determining the exact position of the longitudinal member,

while the upturned hook 6 at the end of the transverse member furnishes a single seat 9 for bearing on the edge of the opposite base flange. These three seats constitute the 5 three points for effective bearing between the anticreeper and the rail and will be described in greater detail hereinafter.

The seats 7 and 9 in combination with the adjacent portions of the transverse member 10 are shoulder seats only and constitute the fulcrum or bearing points for a lever grip on the rail base operating in a horizontal plane, while seat 7 with the adjoining portion of the transverse bar and seat 8 with its 15 upper portion marked 8^a, where the part 4 is bent down over the rail base edge, constitute the fulcrum or bearing points for a lever grip on one base flange operating in a vertical plane. The lever grips are developed 20 in functional operation as hereinafter described.

The tie-abutting part 4 is offset partly under the edge of the rail, providing a short bearing 8^b on the underside of the rail at 25 seat 8. The three surfaces of contact 8, 8^a and 8^b constitute a shallow jaw seat which for the purposes to be served is made as close fitting and as rigid and unyielding in form as possible. This jaw seat has a two-fold 30 purpose as will be disclosed in the description of the installation and functional operations.

As indicated in Fig. 4, the manufactured shape of the device is such that, if it be assumed that the seats 7 and 9 are in position, the jaw seat 8 encroaches inwardly and upwardly on the space required by the rail base on which it is to be seated. Hence, in installation the manufactured shape must be 40 changed, first, by rotating the jaw seat as a whole downwardly in a transverse vertical plane to bring it into line with the rail base and also by moving the jaw seat outwardly away from the opposite seat 9 to clear the 45 edge and take the position of Fig. 2. By the rotation of the jaw seat, a torsional strain is developed in the longitudinal member between the jaw and the root of the V, while the outward movement opens the angle of 50 the V and develops a second torsional strain in the part 5 at the root of the V. A feature especially to be noted here, and one of those distinguishing my present form of device from that of my prior patents, is that the 55 two strains above described are added in action and do not materially diminish the resultant effect. To illustrate:—The rotation in a transverse vertical plane of the jaw downwardly, or clockwise as viewed in Fig. 60 4, producing a torsional strain in the longitudinal member only, would bring the jaw seat 8 inwardly and reduce the space between it and seat 9. As a consequence a greater strain in proportion to that reduction 65 must be developed in part 5 when jaw

seat 8 is brought out to the position of Fig. 2. This development of strain is hereinafter further described in setting forth the manner of installing the anchor.

It is to be noted that the internal strains 70 developed as described in the last paragraph provide a constant initial grip on the rail that is of importance in the maintenance of a genuine lever grip during functional operation. These internal strains will not be increased or materially diminished by the normal tie reaction indicated by the arrow 10 in Fig. 1.

The jaw seat 8 with its bottom part 8^b, in addition to holding the internal strains developed by installation, has the further purpose of holding the free end of the transverse member snug against the base of the rail. This purpose is accomplished directly by the torsional strain in the upper portion 85 of member 2. The upturned hook 6 has a lip 6^a slightly overhanging the rail base edge. This overhanging portion is not essential, however, in holding the device in operative position as in my first prior patent cited. 90

At installation the device is first placed on the rail by hand a little distance away from the tie in the position illustrated in Fig. 5, with the portion 3 of the longitudinal member resting on the rail base and with the 95 transverse member extending under the rail as far as it will go freely with the hook 6 lacking nearly its full thickness of coming into the clear. A hammer blow is next applied in the direction indicated by the arrow 11 in Fig. 5 to bring the device to the position of Fig. 6, rotating the jaw seat downwardly into place about the portion 3 as a fulcrum, but with the hook 6 not yet quite in the clear. The final seating may be 105 accomplished now by placing a crow-bar or other obstruction between the tie and the hook to prevent movement of the hook toward the tie and giving the device an angular hammer blow toward the tie applied at 110 the root of the V as indicated by the arrow 13 in Fig. 3. That operation springs open the angle of the V bringing the hook 6 and its overhanging lip 6^a into the clear while 115 the internal torsional strain in member 2 raises the hook for the seating as shown in Fig. 2.

When the anchor is initially installed, the portion 3 of the longitudinal member engages the upper face of one of the rail base 120 flanges and the hook 6 of the transverse member engages the under side of the other rail base flange, as shown in Fig. 5, and, when so initially installed, the shape of the anchor requires that the engagement with the rail base flange of the jaw seat be effected by the rotation of the free end portion of the longitudinal member, downwardly and inwardly about the portion 3 as 125 a fulcrum. This rotation of the jaw seat 130

takes place in a transverse vertical plane and downwardly and inwardly as stated, or in such a direction that the space between it and the seat 9 at the free end of the transverse member is reduced. Hence, in the final seating of the anchor from the position shown in Fig. 6 to that shown in Fig. 2, the seats 8 and 9 must be spread farther apart than would otherwise be the case, and the torsional strain in the vertical portion 5 of the anchor is thereby correspondingly increased. As stated, the rotational movement of the jaw seat from the position shown in Fig. 5 to that shown in Fig. 6, produces a torsional strain in the portion of the longitudinal member between the jaw seat and the angle of the V-form, and that this torsional strain is maintained by the engagement of the lower shoulder 8^b of the jaw seat with the under side of the rail base flange. It should be noted that this torsional strain is in such a direction that it serves to hold the transverse member upwardly against the underside of the rail base.

By a novel construction of the upper end and surface of hook 6, I am able to do away with the need of the crow bar or other auxiliary means in installation. As illustrated in Figs. 7 and 8, the upper surface of hook 6 and the lip portion 6^a is beveled upwardly away from the rail and downwardly in the direction away from the tie. The result is that with the hook resting in the position shown in Fig. 6, the edge 6^b of this upper surface near the tie is the only part in contact with the lower fillet of the rail base on that side, and will tend to bite into the fillet when driven toward the tie. Because of this bite, or the friction developed at that point, hammer blows applied at the root of the V as indicated, cause the edge 6^b to move outwardly until the hook 6 and lip 6^a clear the base edge.

When the anticreeper is brought to position on the rail it can be moved to its final position abutting the tie by additional hammer blows applied at the root of the V as indicated. In the event a crow bar or other obstruction is employed as described in effecting the seating of the anchor, it is of course removed before the anchor is brought to its final position against the tie.

The bearing face of the seat 9 is beveled preferably so that the rear edge, the edge farther from the tie, will bite into the edge of the rail base like a planer tool or chisel in functional operation. The under surface of lip 6^a overhanging seat 9 is beveled so as to clear above the rail base flange and not to interfere with the perfect bite of edge 9^a.

As specified for the device of my first prior patent cited, that portion of the upper part of longitudinal member 2 adjacent

to the root of the V may be made to lie clear above the upper surface of the base flange. In other words, the vertical face of seat 7 may be of greater depth than the thickness 70 of the rail base flange edge. I take advantage of this possible construction to introduce means whereby in functional operation the bite or holding quality of seat 7 may be increased. Referring to Figs. 6 and 9, when the anticreeper is first applied to the rail, 75 the seat 7 may be set lower than the final level shown in Figs. 1 and 2. In the angle of seat 7 I form small blunt teeth 7^a extending a short distance vertically on part 5 and horizontally on the transverse member and having inclined edges. When the device is installed and is being brought up to the tie the last hammer blows, applied after the tie-abutting portion comes in contact with the tie, operate to lift these teeth into contact with the lower fillet of the base edge. The vertical plane lever grip developed in functional operation by the tie reaction will then cause the teeth to bite the rail.

In functional operation, the tie reaction is received by the tie-abutting member in horizontal direction, as indicated by the arrow 10. Because of the initial friction in installation of bearings 7 and 8, this reaction of course tends to rotate the anchor counter clockwise, as viewed in Fig. 1, so that the bottom portion of the shoulder seat 7 is pressed upwardly and the top portion 8^a of seat 8 downwardly, so that these seats form the fulcrums or bearing points upon the rail base flange of a lever grip operative in a vertical plane. As the reaction force increases sufficiently to produce any tendency to longitudinal movement of the anchor along the rail, the force is transmitted to the transverse member of the anchor through the connection 5, which is outside the seat 7, and thereby establishing a lever grip on the rail base flange operating in a horizontal plane with the seats 9 and 7 acting as the 90 fulcrums or bearing points.

To make the functional operation just described more positive and to stiffen the anticreeper in respect to the lever grip operating in the vertical plane, the lower end of the tie-abutting part 4 is braced by the part 4^a against the underside of member 2 adjacent seat 7, as illustrated and already described. The end of the part 4^a is preferably so shaped as not to come into contact with the rail base edge in normal operation.

The anticreeper is made preferably from square rolled steel bar, and can be manufactured without waste. Fig. 10 is drawn to illustrate a first stage in one way that may be followed in the manufacturing process. The next stage, changing to the lines of Fig. 1, will readily be recognized.

It should be noted that the mechanical features of my anticreeper comprise the 130

spring clamp construction and the use of three distinctive seats or points for bearing on the rail, whereby two combinations of two of the seats held in operative position by the third seat become the fulcrums of genuine lever grips. By genuine lever grip is meant that type wherein the applied force reaches the mechanism outside of the two fulcrums and not between them. It should further be noted that the word "V-form" in this description is used only to cover in an expressive way the general lines of a construction, connecting the three seats of bearing, which will develop and utilize the lever grips described.

I claim as my invention:

1. A spring-clamp anti-creeper for railway rails having forward and rear seats for engaging one of the rail base flanges and an intermediate seat for engaging the other rail base flange, said forward seat being a jaw seat and the connections between said seats requiring, on installation upon the rail base, increase in the distance between the intermediate and jaw seats and the rotary movement of the jaw seat with respect to the other two seats in a transverse vertical plane and in a direction tending to decrease the distance between the jaw and intermediate seats.

2. A rail anchor adapted to be sprung into position upon the rail base, having three seats for effective bearing on the rail base flanges, said seats being connected in V-form by transverse and longitudinal members and located respectively adjacent the junction and the free ends of said members, the seat at the free end of said longitudinal member being a jaw seat and the anchor being arranged to initially engage the rail base in a manner requiring the rotation of the jaw seat to position on the rail base flange in a transverse vertical plane and in a direction tending to decrease the distance between the same and the seat at the free end of said transverse member.

3. A spring-clamp anti-creeper for railway rails comprising transverse and longitudinal members having seats adjacent the free ends and junction respectively of said members, the angle between the seats and the relative shape of the members being arranged to compel, upon installation, the forcing apart in a horizontal direction of the seats at the free ends of said members and the rotation in a transverse vertical plane of the seat at the free end of the longitudinal member relative to the other two seats, the construction being such that each such change in shape, at installation, increases the internal strain developed by the other change in shape.

4. An anti-creeper for railway rails adapted to be sprung into position upon the rail base and comprising transverse and longi-

tudinal members having flange-engaging seats adjacent the ends and junction respectively of said members, the seat at the end of said longitudinal member being a jaw seat and the portions of the longitudinal member extending between the junction and jaw seats being offset inwardly and adapted to extend over the upper face of the rail base flange.

5. An anti-creeper for railway rails adapted to be sprung into position upon the rail base and comprising transverse and longitudinal members having flange-engaging seats adjacent the ends and junction respectively of said members, the seat at the end of said longitudinal member being a jaw seat and a portion of the longitudinal member between the junction and jaw seats being offset inwardly and adapted to bear upon the upper face of the rail base flange in the process of installation and form a fulcrum about which the jaw seat is rotated downwardly as it is forced into position on the rail base flange.

6. A V-form, spring-clamped rail anchor having forward and rear seats for effective bearing on one rail base flange and a third intermediate seat for effective bearing upon the other rail flange, said forward and intermediate seats being arranged adjacent the free ends of the members of the V-form and the rear seat adjacent the junction of the members, the said forward seat being a jaw seat and arranged to force the transverse member upwardly against the rail base, the free end of the transverse member having means for biting into the rail base flange prior to the engagement of the intermediate seat therewith, whereby the anchor may be installed by engaging the front and rear seats with one rail base flange and driving the same forwardly thereon.

7. A spring-clamp anti-creeper having three seats for effective bearing on the rail base flanges and adapted in functional operation to develop lever grips upon the rail base, both in vertical and horizontal planes, with one of said seats forming a fulcrum for both of such lever grips and such seat having an inclined cutting edge or edges adapted to engage the edge of the rail base flange and have its bite thereon increased in functional operation by the lever grip acting in a vertical plane.

8. A V-form spring-clamp rail anchor comprising longitudinal and diagonal transverse members having three seats for effective bearing on the rail base flanges located at the junction and free ends of said members, the seat at the forward end of said longitudinal member being a jaw seat arranged to snugly embrace the rail base flange and thereby force the transverse member upwardly against the rail base, the portion of the longitudinal member between the

5

junction and jaw seats being offset inwardly and adapted to extend over the rail base flange.

9. A V-form spring-clamp anti-creeper for railway rails comprising longitudinal and diagonal transverse members and having three seats for effective bearing on the rail base flanges located respectively adjacent the junction and free ends of said members, said longitudinal member having at its free end a depending integral tie-abutting portion and the latter having a brace extending upwardly and rearwardly from its lower end to the rear end portion of said longitudinal member.

10. A resilient V-form rail anchor comprising longitudinal and transverse members and having flange-engaging seats at the junction and free ends of said members, and the construction requiring, upon installation, the spreading in a horizontal direction of the seats at the free ends of said members and the torsional distortion in a transverse vertical plane of the free end portion of said longitudinal member and in such a direction as to increase the required amount of spreading of the seats at the free ends of the members.

11. An anticreeper for railway rails adapted to be sprung into position upon the rail base and comprising longitudinal and transverse members with forward and rear seats adjacent the ends of the longitudinal member adapted to engage one of the rail base flanges and an intermediate seat adjacent the end of the transverse member for engaging the other rail base flange, a portion of the longitudinal member between the forward and rear seats being offset inwardly and adapted to bear upon the upper face of the rail base flange in the process of installation and form a fulcrum about which the forward seat is rotated downwardly and inwardly as it is forced into position on the rail base flange, said forward seat having

an inwardly offset shoulder adapted to bear against the underside of the rail base flange.

12. A V-form, spring clamp rail anchor, comprising longitudinal and diagonal transverse members having forward and rear rail-engaging seats adjacent the ends of the longitudinal member and an intermediate rail-engaging seat at the free end of the transverse member, a portion of the longitudinal member between said forward and rear seats being arranged to overhang one of the rail base flanges, the construction of the anchor requiring upon installation on the rail base, the development of a torsional strain in the longitudinal member in a direction tending to force the transverse member upwardly toward the rail base.

13. A one-piece, V-form spring clamp rail anchor, comprising longitudinal and diagonal transverse members connected by a vertical portion and having a rear rail-engaging seat adjacent the junction of the members and forward and intermediate rail-engaging seats adjacent the free ends of the longitudinal and transverse members respectively, said members being arranged to be sprung apart in horizontal direction on installation thereby developing a torsion in said vertical portion that tends to force said members together, said forward seat having a shoulder adapted to extend beneath the rail base and a portion of said longitudinal member between the forward and rear seats being inwardly offset to engage the upper face of the rail base flange on installation and form a fulcrum about which the forward seat must be forced downwardly and inwardly to position on the rail base flange and thereby develop a torsional strain in said longitudinal member that will tend to force the shoulder of the forward seat and the transverse member upwardly toward the rail base.

WILLIAM S. WESTON.
